(57) **CLAIM**

The ornamental design for a dispenser with trigger, as shown and described.

DESCRIPTION

FIG. 1 is a perspective view of the dispenser with trigger which embodies our new design;

FIG. 2 is a front elevational view;

FIG. 3 is a back elevational view;

FIG. 4 is a left side elevational view;

FIG. 5 is a right side elevational view;

FIG. 6 is a top plan view; and,

FIG. 7 is a bottom plan view.

The broken lines are included for the purpose of illustrating portions of the dispenser with trigger that form no part of the claimed design.
